UNITED STATES PATENT OFFICE.

ALVIN SQUIRES AND ELISHA B. SQUIRES, OF HARTFORD, CONNECTICUT.

OYSTER-TRANSPORTATION CAN.

SPECIFICATION forming part of Letters Patent No. 240,281, dated April 19, 1881.

Application filed August 30, 1880. (No model.)

To all whom it may concern:

Be it known that we, ALVIN SQUIRES and ELISHA B. SQUIRES, of Hartford, in the county of Hartford and State of Connecticut, have invented a certain new and useful Improvement in Oyster-Transportation Cans, of which the following is a description, reference being had to the accompanying drawings, where—

Figure 1 is a central vertical section. Fig. 10 2 is a top view of the inner can. Fig. 3 is a side view of same. Fig. 4 is a side view from the opposite side from that shown in Fig. 3. Fig. 5 is a detail view of the side and lid of the outer case.

15 The apparatus is designed for use in the transportation of oysters, keeping them refrigerated the while.

The letter *a* denotes an outer wooden casing or tub; *b*, the cover thereof; *c*, a rubber gasket 20 to keep the joining tight; *d*, nuts to secure the cover in place, taking upon the bolts *e*, which, fast to the tub *a*, rise through holes in cover *b* to receive the nuts.

The letter *f* denotes an inner metallic can 25 for holding the oysters, with a space between it and the tub *a* to hold refrigerating material. *g* denotes steady-blocks fixed to the inside of the tub to hold the top of the can from swaying.

The letter *h* denotes the lid or cover of the 30 can, bearing a laterally-extending pintle, *i*, taking into the loop *j*, fixed to the can, this to form a hinge which permits the bodily removal of the lid. *k* denotes a hasp taking upon the staple *l*, thus permitting the lid *h* to be locked 35 on by a padlock.

The letter *m* denotes a set-screw running through the bottom of the can into the bottom of the tub, and holding can and tub securely together.

n denotes a rubber packing-ring, which may be inside or outside the can, to keep tight the hole through which screw *m* passes.

We claim as our invention—

1. In combination, the tub *a*, the can *f*, the 45 screw *m*, and the packing *n*, all substantially as described, and for the purpose set forth.

2. The tub *a*, provided with bolts *e* and steady-blocks *g*, the cover *b* and nuts *d*, the can *f*, provided with loop *j* and staple *l*, the 50 lid *h*, provided with pintle *i* and hasp *k*, the set-screw *m*, and the packing *n*, all combined substantially as described.

ALVIN SQUIRES.
